UNITED STATES PATENT OFFICE.

JOHN KIEWICZ, OF BOSTON, MASSACHUSETTS, ASSIGNOR TO THE REECE BUTTON HOLE MACHINE COMPANY, OF BOSTON, MASSACHUSETTS, A CORPORATION OF MAINE.

DRIVING AND STOPPING MECHANISM.

1,326,668.

Specification of Letters Patent. Patented Dec. 30, 1919.

Application filed December 15, 1917. Serial No. 207,235.

To all whom it may concern:

Be it known that I, JOHN KIEWICZ, a citizen of the United States, residing at Boston, county of Suffolk, State of Massachusetts, have invented an Improvement in Driving and Stopping Mechanism, of which the following description, in connection with the accompanying drawing, is a specification, like characters on the drawing representing like parts.

This invention relates to driving and stopping mechanism of that type adapted to drive a machine that is constructed to perform a predetermined cycle of operations and to bring said machine to rest in a predetermined position when the cycle of operations is completed. The object of the invention is to provide a novel driving and stopping mechanism which is constructed so that when the machine is to be started the driving mechanism will be held positively inoperative until the stop device has been entirely released and will be rendered operative to start the machine in operation by the releasing movement of the stop device.

My invention is adapted for use in driving a great variety of machines that are constructed to perform a predetermined cycle of operations and then to be brought to rest. As illustrative of one machine of this type I would refer to a buttonhole sewing machine and I have herein chosen to illustrate the invention as it would be applied to such a machine, although, as stated above, the invention is equally applicable to other machines.

In order to give an understanding of the invention I have, therefore, illustrated it as it might be applied to a buttonhole sewing machine, and in the drawings, Figure 1 is a side view of a sewing machine which is controlled by my improved device;

Fig. 2 is a top plan view showing the parts in the position they assume when the machine is at rest;

Fig. 3 is a side view of the driving clutch;

Fig. 4 is a section on the line 4-4, Fig. 3;

Fig. 5 is a view similar to Fig. 2, showing the parts in the position they assume when the stop device is being released;

Fig. 6 is a detail view of the lever for actuating the controlling member.

Fig. 7 is a section on the line 7-7, Fig. 1;

Fig. 8 is a section on the line 8-8, Fig. 4.

In Fig 1 I have indicated generally at 1 a buttonhole sewing machine of the type shown in United States Patent No. 1,188,942, dated June 27, 1916, and which comprises stitch-forming mechanism for forming the edge stitches over a buttonhole. Said stitch-forming mechanism includes the upper reciprocating eye-pointed needle 3 and an under thread mechanism indicated generally at 4, said stitch-forming mechanism being actuated from a driving shaft 2. The feeding of the work during the formation of the buttonhole and some of the other operations of the machine are controlled from a feed cam 5 which is rotatably mounted in the bed of the machine.

Inasmuch as the present invention relates solely to the driving and stopping mechanism by which the movements of the shaft 2 are controlled, I do not think it necessary to give any further description of the buttonhole sewing machine 1.

The shaft 2 is driven from a driving pulley 6, and said pulley is rendered operative or inoperative by the movement of an actuating device 14, movement of said device toward the pulley causing the pulley to be operative and movement in the opposite direction causing the pulley to be inoperative. This driving pulley 6 may be a pulley fast on the shaft onto and from which a driving belt is shifted, in which case the member 14 would take the form of a belt shipper, or said pulley may be loose on the shaft and may be connected thereto by a suitable clutch device which is rendered operative or inoperative by the member 14, in which case said member 14 becomes a clutch actuator. In the construction shown the pulley 6 is loosely mounted on the shaft and is adapted to be connected thereto by means of a friction clutch which comprises an expanding clutch ring 7 which is secured to and rotates with the driving pulley 6, said ring being adapted to be expanded into clutching engagement with the interior clutch surface 8 formed on a clutch member 9 which is fast on the shaft 2. The clutch ring 7 is expanded by means of a clutch-expanding member 10 situated between the ends of the clutch ring and journaled in the pulley 6. This clutch-expanding member has an arm 11 fast thereon which carries at its end a screw 12 that is adapted to be engaged by a clutch-

actuating cone 13 slidably mounted on the shaft 2. The movement of the cone toward the pulley causes the cone surface thereof to act on the screw 12 and thus turn 5 the lever 11 in a direction to expand the clutch into operative engagement with the clutch surface 8, while movement of the cone 13 away from the driving pulley will release the clutch. The cone clutch 13 is given its movement in one direction or the other by the clutch actuator 14 having a forked end 15 which is received in a groove 16 formed in the clutch cone.

At the end of each cycle of operations the 15 shaft 2 is brought to rest in a predetermined position by means of a stop device shown as a stop cam 17 fast on the shaft 2 and a co-operating stop member 20 which is yieldingly carried by an arm 21 fast on a controlling member 22 in the form of a rod 20 slidably mounted in suitable bearings 23 formed on the machine. The stop cam 17 is formed with the eccentric or cam surface 18 and with the stop notch 19 which is 25 adapted to receive the stop member 20 when the machine is at rest, and the stop member 20 is carried by a plunger 26 slidably mounted in the arm 20 and backed by a spring 27. While the machine is in operation, the controller 22 is in a position to hold the stop member 20 at one side of the eccentric portion 18 of the stop cam and against the concentric portion 25 thereof, as shown in dotted lines, Fig. 7, but when 30 the cycle of operations has been completed, the controller 22 is moved into the position shown in Fig. 2, thereby moving the stop member 20 in the direction of the axis of the shaft 2 and in position to engage the eccentric portion 18 of the stop cam 17. The stop cam has a low portion 24 which is of the same diameter as the concentric portion 25 thereof, and when the stop member is moved toward the stop cam, as above 35 described, at the end of the cycle of operations, said stop member passes onto the low portion 24 of the cam and thence onto the eccentric portion 18 thereby producing a braking effect until the notch 19 comes 40 opposite the end of the stop member when the latter swings into the notch, thereby positively bringing the shaft to rest. This return movement of the controller 22 as well as the movement which causes the stop member 20 to enter the notch 19 is secured 45 from a pulling spring 28 which is fastened at one end to the frame of the machine, as shown at 29, and the other end of which is secured to a pin 30 extending from a collar 31 fast on the controller 22. The spring 28 is situated at a slight inclination, as shown in Figs. 2 and 5, so that it not only pulls downwardly on the arm 20 and thus tends to turn the controller 22 in a direction 50 to cause the stop member 20 to enter the

notch 19, but it also tends to pull the controller in a direction to carry the stop member axially toward the stop cam 17.

The shaft 2 is set in operation by forcing the controller 22 in a direction to carry 70 the arm 21 and stop member 20 laterally out of engagement with the stop cam 17, and this may be done by hand or by any suitable device. The mechanism herein shown is so constructed that when the controller is thus 75 moved into position to carry the stop member laterally out of engagement with the stop cam, the actuator 14, whether it operates a clutch or is in the nature of a belt shipper, will be held inoperative until the 80 stop member is entirely free from the stop cam, and then said actuator will become operative so that there will be no tendency to start the shaft 2 in rotation until after the stop member is entirely released from the 85 stop cam. The actuator 14 is carried by a sleeve 32 which is slidably mounted on the controller 22, said sleeve being yieldingly connected to the controller by means of a pulling spring 33, one end of which is fastened to the sleeve 32 and the other end of which is fastened to the collar 34 that is fast on the controller. The sleeve 32 has a latch member 35 pivoted thereto at 36, said latch member being formed with a shoulder 90 37 which is adapted to engage an abutment herein shown as a rib 38 forming part of the frame of the machine when the clutch actuator 14 is moved into a position to render the clutch inoperative. The latch 35 100 will thus hold the clutch in its inoperative position. When the controller 22 is moved in a direction to carry the stop member 20 laterally out of engagement with the stop cam, as shown in Fig. 5, the clutch actuator 105 14 will remain stationary due to the engagement of the latch 35 with the abutment 38 and the spring 33 will thus be placed under tension. Just as the stop member 20 becomes free from the stop cam 17, 110 the latch 35 is released from the abutment, and when this occurs the spring 33 moves the sleeve 32 thereby to carry the actuator 14 toward the pulley and to throw the clutch into operation. This clutch-actuating movement of the clutch actuator, however, does 115 not occur until after the stop member is entirely free from the stop cam, and there is thus no overlapping of operations between the release of the stop cam and the 120 engagement of the clutch. In the present embodiment of the invention I make use of the stop-releasing movement of the arm 21 to disengage the latch 35 from the abutment. 125

Upon referring to Figs. 1 and 7 it will be seen that the bottom of the notch 19 is at a greater radial distance from the center of the shaft 2 than the portion 25 of the stop cam and consequently when the stop mem- 130

ber 20 has been carried laterally out of the notch 19, the pulling action of the spring 28 will turn the controller 22 slightly so as to bring the stop member against the portion 5 25, as seen in dotted lines Fig. 7. This slight upward movement of the arm 21 from the position shown in Fig. 1 to that it occupies when the stop member engages the portion 25 is made use of to release the latch 35. 10 The latch 35 has rigid therewith a bracket 39 in which is adjustably mounted a stop screw 40, said screw being situated over the arm 21 and being adjusted so that when the arm 21 is in the position shown in Fig. 1 15 and the latch 35 is in operative engagement with the abutment 38, said stop screw will just have contact with the arm 21. When the arm 21 partakes of its slight upward movement after being freed from the notch 20 19 of the stop cam, such upward movement will act through the set screw 40 to raise the latch and thus release the latch from the abutment. It will thus be seen that I have provided herein a device which embodies both a stop motion and a driving mechanism and by which when the machine is to be set in operation, the driving mechanism will be positively held inoperative until the stop device is entirely released so that 30 there will be no tendency of the driving mechanism to start the driving shaft in operation while the stop motion is still operative.

Further, it will be seen that in the device 35 herein shown, the releasing movement of the stop motion is made use of to render the driving mechanism effective.

I have above stated that the controlling member 22 might be moved into position to 40 release the stop device by any suitable means. Where the device is used for controlling the shaft which drives the stitch-forming mechanism of a buttonhole sewing machine, I propose to control the movements 45 of the controller 22 from the main cam 5. 41 is an elbow-lever pivoted to the frame at 420, one arm of said lever being forked and having engagement with the pin 30 and the other arm also being forked and having engagement with the offset end 42 of a lever 43 which is pivotally mounted on a stud 44. The front end of the lever 43 is situated over 50 a pin 45 which is mounted in the frame of the sewing machine for vertical movement, and the lower end of the pin is adapted to be actuated by a cam portion 46 formed on the main cam 5 of the machine. When the high portion of the cam 46 passes under the pin 45, the latter is raised thereby raising 55 the front end of the lever 43 and depressing the rear end thereof. This movement of the lever 43 turns the bell crank 41 in a direction to move the controlling member 22 into the position shown in Fig. 5 from that 60 shown in Fig. 2. The controlling member

will be held in this position so long as the high portion of the cam 46 engages the pin, but when the end 47 of the high portion passes under the pin 45, then said pin will drop, thus allowing the controller to be carried into the position shown in Fig. 2 and the stop member 20 to be brought into operative engagement with the stop cam. 70

In the buttonhole sewing machine shown in the patent referred to No. 1,188,942, the 75 main cam 5 is set in operation thereby to cut the buttonhole before the shaft 2 which operates the stitch-forming mechanism is set in operation, and thus the movement of the cam 5 may be readily made use of to control 80 the movement of the controller 22, but the particular means by which the controller 22 is actuated is not essential to the invention.

While I have illustrated the invention herein as it might be applied to a buttonhole sewing machine, yet I would state that it can be equally well used in connection with other machines that have a stop motion and a driving mechanism co-operating to drive the machine and to bring it to rest 90 after a predetermined cycle of operations.

I claim:

1. In a driving and stopping mechanism of the type having a driving shaft, a driving mechanism for rotating said shaft and a stop device for bringing the shaft to rest at a predetermined point when the driving mechanism is rendered inoperative, the combination with a controlling member movable in the direction of the length of the shaft for releasing the stop device, of an actuator for rendering the driving mechanism operative or inoperative, and means operative while the controlling member is moved to release the stop device to hold the driving mechanism inoperative until after the stop device is fully released. 100

2. In a driving and stopping mechanism of the type having a driving shaft, a driving mechanism for rotating said shaft and a stop device for bringing the shaft to rest at a predetermined point when the driving mechanism is rendered inoperative, the combination with a controlling member for releasing the stop device, of an actuator for rendering the driving mechanism operative or inoperative, a latch movable relative to the actuator for preventing movement of the latter while the controlling member is being moved to release the stop device, and means to move the latch and thereby release it when the stop device is fully released thereby to permit the actuator to be moved to render the driving mechanism operative. 110

3. In a device of the class described, the combination with a driving shaft, of a driving mechanism for rotating said shaft, a stop device for bringing the shaft to rest at a predetermined point when the driving 120 125 130

mechanism is rendered inoperative, automatically-operative means to render the driving mechanism operative, a controlling member for releasing the stop device, a pivotally-mounted latch for holding said automatically-operative means inoperative, and means to release the latch after the stop device has been fully released.

4. In a driving and stop motion of the type comprising a driving shaft, a clutch for driving said shaft, and a stop device for bringing the shaft to rest at a predetermined point when the clutch is released, the combination with a controlling member for releasing the stop device, of a clutch actuator, a spring to shift the clutch actuator into operative position, a latch carried by but movable relative to said actuator to hold the latter from movement while the stop device is being released, and means to move the latch and thereby release it after the stop device has been fully released.

5. In a driving and stop motion of the type comprising a driving shaft, a clutch for driving said shaft, and a stop device for bringing the shaft to rest at a predetermined point when the clutch is released, the combination with a controlling member for releasing the stop device, of a clutch actuator, a spring to shift the clutch actuator into operative position, means to place the spring under tension by the movement of the controlling member which releases the stop device, and means actuated by the release of the stop device to render the spring operative to shift the clutch.

6. In a driving and stop motion of the type comprising a driving shaft, a clutch for driving said shaft, and a stop device for bringing the shaft to rest at a predetermined point when the clutch is released, the combination with a controlling member for releasing the stop device, of a clutch actuator, a spring to shift the clutch actuator into operative position, means to place the spring under tension by the movement of the controlling member which releases the stop device, a latch to hold the clutch actuator from movement, and means to release the latch by the releasing movement of the stop device whereby said spring throws the clutch into operation.

7. In a driving and stopping mechanism

of the type comprising a driving shaft, a clutch for driving said shaft, and a stop device for bringing the shaft to rest, the combination with a controlling member for releasing the stop device, of automatically-operative clutch-actuating means, a latch carried by but movable relative to said means for holding the latter inoperative while the stop device is being released, and means for moving the latch to release it thereby to allow the clutch to be engaged after the stop device has been fully released.

8. In a driving and stopping mechanism of the type comprising a driving shaft, a clutch for driving said shaft, and a stop device for bringing the shaft to rest at a predetermined point, the combination with a controlling member for releasing the stop device, of a spring-impelled clutch actuator, a latch pivotally mounted on the actuator for holding the latter from movement while the stop device is being released, and means to release the latch when the stop device is fully released.

9. In a driving and stopping mechanism of the type comprising a driving shaft, a clutch for driving said shaft, and a stop device for bringing the shaft to rest at a predetermined point, the combination with a controlling member for releasing the stop device, of a spring-impelled clutch actuator, a latch pivotally mounted on the actuator for holding the latter from movement while the stop device is being released, and means to release the latch by the final movement of the stop device as it is released.

10. In a device of the class described, the combination with a driving shaft, of a driving mechanism for rotating said shaft, a stop device for bringing the shaft to rest at a predetermined point when the driving mechanism is rendered inoperative, automatically-operative means to render the driving mechanism operative, a controlling member for releasing the stop device, a latch movable independently of the stop device for holding said automatically-operative means inoperative, and means to release the latch after the stop device has been fully released.

In testimony whereof I have signed my name to this specification.

JOHN KIEWICZ.
